UNITED STATES PATENT OFFICE.

WILLIAM W. MORRAL, OF MORRAL, OHIO.

GREEN-CORN-HUSKING MACHINE.

Application filed January 16, 1922. Serial No. 529,633.

To all whom it may concern:

Be it known that I, WILLIAM W. MORRAL, a citizen of the United States, residing at Morral, in the county of Marion and State 5 of Ohio, have invented a certain new and useful Improvement in Green-Corn-Husk- ing Machines, of which the following is a specification.

This invention relates more particularly 10 to machines designed to butt and husk two files or rows of green corn, an example of such machine being exhibited in Letters Patent of the United States, No. 1,314,353, dated August 26, 1919.

15 The object of the present invention is to simplify and improve the construction of such machines whereby they are compacted and better balanced in the application of power for operating them.

20 The invention is embodied in the example herein shown and described, the features of novelty being finally claimed.

In the accompanying drawing—

25 Figure 1 is a view in side elevation with parts broken out and omitted.

Fig. 2 is a vertical section on the line II— II Fig. 1 looking to the left.

Fig. 3 is a detail in top plan view of the husking rolls.

30 Fig. 4 is a modification of the belt for carrying the ears along the husking rolls.

The present machine includes a frame having side members 1 supported by legs 2. Traveling in connection with a suitable up- 35 wardly inclined bed 18 in the upper portion of the frame is an endless belt or carrier 19 traveling on sprockets 24 and having flights 51 by means of which the ears to be husked are carried to the feeding rolls

40 34, gaging screws 25 and butt removers 8, one set of these rolls, screws and removers being arranged on each side of the machine with suitable means for their similar and simultaneous operation.

45 Journaled below the lower reach of the belt 19 and transversely of the direction of motion of the latter are two pairs of husking rolls 110, 110^a and 111, 111^a of usual form all geared together so that the members of 50 each pair turn toward each other at the top to draw the husks from an ear deposited in the bite or valley between the members of the pairs at their upper sides. One roll of each pair is slightly higher than the other 55 to cause a rolling of the ear as it is being husked. Longitudinally between the two

pairs of husking rolls is secured a wall or strip 35 for the purpose of confining the ears to the rolls between which they are deposited. The two pairs of rolls are also 60 flanked longitudinally by strips or walls 35^a on which ride the end of the flights hereinafter described.

Arranged around the upper end of carrier 19 is a curved hood or guide plate 63 65 one side of which terminates to cause the release of the ears butted at one side of the machine onto the first pair of husking rolls 110, 110^a while the other is extended as seen at 68^a (see Fig. 3) to permit the butted ears 70 at the other side to be carried to the second pair of rolls 111, 111^a.

To feed the ears along the husking rolls 110, 110^a and 111, 111^a there is arranged to travel on sprocket wheels 39 and 40 a belt 75 comprised of a pair of endless sprocket chains 37, 37 between and to which are secured blades or flights 38 each formed with projections 38^a to extend into the bites or valleys between the rolls so as to insure engagement of the flight with the ear and each provided with a notch 38^b to permit it to travel over the strip 35. The belt thus described it will be noted is arranged to travel around the lower reach of the main feed 80 belt 19 without interfering with the latter and the two belts can operate to perform their respective functions at the same time. Instead of using the belt with the flights 38 as shown in Fig. 1 said flights can be ar- 85 ranged on a chain moving in a horizontal plane as shown in Fig. 4.

The main power shaft is located at 32, said shaft having affixed thereto a belt pulley which is to be driven in the direction 90 indicated by the arrow near it (see Fig. 1). From the shaft 32 power is transmitted by sprocket chain 81 to the shaft of the husking roll 110^a, which being thereby rotated in the direction indicated by the arrow 100 thereon turns all the husking rolls in the desired direction as before indicated. From a suitable sprocket wheel on the shaft of the husking roll 110^a a sprocket chain 82 drives a shaft 42 for operating bevel gears 43, 43^a and the sprocket chains 37 to feed the ears along the husking rolls. From a suitable sprocket wheel on the shaft 43 is a sprocket chain 26 that travels over a sprocket wheel 125 on shaft 21 and sprocket 105 wheel 108 on shaft 106. The shaft 21 contains suitable usual sprockets for driving 110

the carrier belt 19 while the shaft 106 drives a belt 105 in the lower portion of the main frame for carrying away the husks drawn through the husking rolls and dropped on to said belt 105.

The feeding rolls 34, gaging rolls 25 and butt removers 8 are provided with suitable means or gearing to be driven from the main power shaft 32 as shown or as developed in the "Morral" machine in the patented and practical art and needs no detailed description herein and especially as such details do not constitute a part of the present invention.

15 The operation of the present invention is briefly this: The ears of corn to be husked are placed in two files or rows on the front, that is the right hand end of the table as shown in Fig. 1, in advance of the flights 51 and the ears are by these flights carried cross-wise of their length to the butt removers 8, the latter cutting off the butts. Beyond the butt removers said flights carry the ears through the guide or hood 63 to 20 the husking rolls one file of ears being delivered to the pair of rolls 110, 110^a and the other to the pair of rolls 111, 111^a. Upon their deposition in the husking rolls the ears are carried by the flights 38, meaning 25 while being deprived of their husks, to the side of the machine where they are discharged into a suitable receptacle to be carried away.

The drawings show a double husker but I 30 claim as my invention an improvement on single as on double corn husking machines.

The forms of the parts can be changed without departing from the gist of the invention as claimed. For example other 40 means can be employed for causing the ears to move along the husking rolls.

What I claim is:

1. In a machine for husking an ear of corn, the combination with butt removing means, and a belt for carrying the ears to be husked to and beyond said butt removing means, a pair of husking rolls lying transversely of the direction of motion of said belt, and in a plane intersecting the plane of the belt, and a belt provided with flights, said last named belt extending around the lower reach of the first named belt for moving the ear along said husking rolls, said husking rolls lying under the 50 lower reach of the second named belt.

2. In a machine for husking two files of ears of corn, the combination with butt removing means and a belt adapted to carry two files or rows of corn to be husked to and beyond said butt removing means, two pairs of husking rolls lying transversely of the direction of motion of said belt and in a plane intersecting the plane of the belt, means for causing the butted ears of one 60 file to be delivered to one pair of the said

rolls and the other file of such ears to be delivered to the other pair of said rolls, and a belt extending around a reach of the first named belt for moving the ears along said husking rolls.

70

3. In a machine for husking two files of ears of corn, the combination with butt removing means and a belt adapted to carry two files or rows of corn to be husked to and beyond said butt removing means, two pairs of husking rolls lying transversely of the direction of motion of said belt and in a plane intersecting the plane of the belt, a longitudinal wall between said pairs of husking rolls, means for causing the butted ears of one file to be delivered to one pair of the said rolls and the other file of said ears to be delivered to the other pair of said rolls, and a belt extending around a reach of the first named belt for moving the ears along said husking rolls.

80

4. In a machine for husking two files of ears of corn, the combination with butt removing means, and a belt having upper and lower reaches adapted to carry two files or rows of corn to be husked to and beyond said butt removing means, two pairs of husking rolls lying transversely of the direction of motion of said belt, guiding means for the butted ears beyond said butt removing means and means for causing the ears of one file to be delivered to one pair of said rolls and the ears of the other file to be delivered to the other pair of said rolls, and a belt provided with flights extending 90

85

around the lower reach of said first named belt for moving the ears along said husking rolls.

95

5. In a machine for husking two files of ears of corn, the combination with butt removing means and a belt having upper and lower reaches adapted to carry two files or rows of corn to be husked to and beyond said butt removing means, two pairs of husking rolls lying transversely of the direction of said belt and in a plane intersecting the plane of the belt, guiding means for the butted ears beyond said butt removing means and means for causing the ears of one file to be delivered to one pair of said rolls and the ears of the other file to be delivered to the other pair of said rolls, and a belt provided with flights for moving the ears along said husking rolls.

100

6. In a machine for husking two files of ears of corn, the combination with butt removing means and means for carrying the ears in adjacent parallel files to be husked to and beyond said butt removing means, of two pairs of husking rolls, guides for causing the ears of one file to be delivered to one pair only of said rolls and the ears of the other file to be delivered to the other pair only of said rolls and a belt provided with flights extending across both 110

115

120

125

130

pairs of husking rolls for positively moving the ears along said husking rolls.

7. In a machine for husking an ear of corn, the combination with butt removing means, and a belt for carrying the ears to be husked to and beyond said butt removing means, a pair of husking rolls lying transversely of the direction of motion of said belt and in a plane intersecting the plane of the first named belt, a belt provided with flights for moving the ear along said husking rolls said last named belt extending around a reach of the last named belt and rails upon which the flights of said last named belt are supported and travel.

8. In a machine for husking ears of corn, the combination of a belt for feeding the ears crosswise of their length, a pair of husking rolls the bite of which lies transversely of the feed belt and under said belt with the plane of said bite intersecting the plane of movement of the feed belt, a belt having flights for feeding the ears in the direction of their length along said bite, and means for guiding the ears around the turn of the feeding belt to said husking rolls.

9. In a machine for husking two files of ears of corn, the combination with two butt

removing devices and means located between the two butt removing devices for carrying the ears in adjacent parallel files to and beyond said butt removing devices, of two pairs of husking rolls, guides for causing the ears of one file to be delivered to one pair only of said husking rolls and the ears of the other file to be delivered to the other pair only of said husking rolls, and a belt provided with flights for positively moving the ears along said pairs of husking rolls.

10. In a machine for husking two files of ears of corn, the combination with two butt removing devices and means located between the two butt removing devices for carrying the ears in adjacent parallel files to and beyond said butt removing devices, of two pairs of husking rolls, guides for causing the ears of one file to be delivered to one pair only of said husking rolls and the ears of the other file to be delivered to the other pair only of said husking rolls, and a belt provided with flights extending across both pairs of husking rolls for positively moving the ears along said husking rolls.

WILLIAM W. MORRAL.
